UNITED STATES PATENT OFFICE.

PATRICK SHAUGHNESSEY O'DONNELL, OF LONDON, ENGLAND.

TELEPHONE-MOUTHPIECE DISINFECTOR.

Application filed January 3, 1924. Serial No. 684,236.

To all whom it may concern:

Be it known that PATRICK SHAUGHNESSEY O'DONNELL, a subject of the King of Great Britain, of 24 Mornington Crescent, London, NW. 1, in the county of London, England (whose post-office address is 24 Mornington Crescent, London, NW. 1, England), has invented certain new and useful Improvements in Telephone-Mouthpiece Disinfectors, of which the following is a specification.

This invention for improvements in apparatus for use in disinfecting telephone mouth-pieces has for its object to remove all danger of infection from the use of telephones and to provide improved means whereby a disinfectant or germicide may be held in a convenient form and in a convenient manner in close proximity to the mouth-piece of the telephone without altering the mouth-piece or interfering with the speaker.

The invention comprises a small light container, holder or case of metal or other material and preferably of tubular form and a spring clip arranged to embrace the neck portion of the mouth-piece of the telephone transmitter and to support the container just above the front edge of the same.

A powerful volatile germicide and disinfectant such as a solution of formaldehyde for example made up in cartridge or other convenient form is inserted in the container and delivers the vapour across the mouth-piece of the transmitter through suitable slots or openings formed in the container.

In one way of carrying out the invention the container or holder which may be made of metal, consists of a tubular case with a removable cover or cap at one end and a series of longitudinal slots or openings near the middle. A lug fixed transversely to the case near the middle of its length is connected with an extension or lug carried on a spring clip formed to embrace the narrow portion of the mouth-piece of the telephone transmitter. The connection between the container or holder for the disinfectant and its support is preferably one which permits of the container being moved backward or forward to some extent in relation to its support in order that if necessary the container, which normally lies horizontally just above the mouth-piece may be pushed back to enable a speaker to put his mouth close

up to the mouth-piece, as for example when telephoning over long distances. This can be effected by employing either a sliding or pivotal connection.

A suitable cartridge for use in the container consists of a closed receptacle containing a volatile disinfectant liquid and capable of being punctured to release the contents gradually, and an enclosing tube or sleeve of unsized paper closed at its ends and arranged to absorb and diffuse the liquid contents of the receptacle which escape gradually after the receptacle has been punctured. The cartridges can be easily removed and renewed as required. It will be understood, however, that any other suitable form of disinfecting medium could be employed in the container or holder.

The invention is more fully described with reference to the accompanying drawings in which:

Figs. 1 and 2 illustrate in side and front elevation respectively one practical embodiment of this invention in which the disinfecting means is pivotally supported.

Fig. 3 is a sectional view of the same drawn to a larger scale.

Figs. 4 and 5 are side and front elevation respectively of a modified embodiment of the invention having the disinfecting means mounted so as to be capable of sliding.

Fig. 6 is a detail sectional view taken on the line 6—6 in Fig. 4.

Figs. 7 and 8 illustrate in plan and sectional side elevation respectively a still further modified embodiment of the invention.

Referring to Figs. 1 to 3 it will be seen that the apparatus comprises a cylindrical container or case *a* preferably of thin metal, having a removable cap or cover *b* at one end enabling the container to be opened for the introduction of a disinfecting cartridge, and a plurality of longitudinal slots or openings *c* along the centre portion of the case through which the vapour of the disinfectant is delivered to the telephone mouth-piece *d*. A lug *e* brazed or sweated to the case at its centre of length projects a short distance from the case and is formed near the end with a pair of trunnions *e'* arranged in a line parallel with the longitudinal axis of the case.

A spring clip *f* arranged to embrace the narrow neck portion of the telephone mouth-

piece has attached at its centre of length a lug *g* projecting towards the front of the telephone mouth-piece *d*, and the lateral edges *g'* of this lug are turned upwards and 5 perforated so as to form suitable bearings in which the trunnions *e'* are engaged. This method of mounting the device enables the case *a* to be moved when required from a position just over the edge of the mouth-piece 10 *d* backwards to a position just over the spring clip *f* as indicated by chain lines in Fig. 1. A spring tongue *h* riveted to the lug *g* and clip *f* acts upon the extremity of the lug *e* and serves to retain the case *a* in either 15 of its extreme positions. The forward extremity of the lug *g* is turned up to form a stop or support for the case *a* when in the forward position.

The case *a* is intended to accommodate a 20 volatile disinfecting material the vapour from which is diffused through the slots *c* over the telephone mouth-piece and for convenience this disinfectant is preferably employed in cartridge form as shown at *i* in 25 Fig. 3. A suitable cartridge for such use consists of a fluid tight container capable of being punctured, packed with an absorbent material saturated with a disinfectant and germicide such as a solution of formaldehyde. When inserted in the case *a* the cartridge is pierced with some suitable sharp instrument and is then capable of delivering 30 a disinfectant vapour about the telephone mouth-piece. Upon exhaustion of the fluid 35 contents of a cartridge the cartridge may be removed and replaced by a fresh cartridge.

The modified construction illustrated in 40 Figs. 4 to 6 is similar to that just described except that the case *a* instead of being mounted to pivot on the lug on the spring clip *f* is arranged to slide for the purpose of adjustment. To this end the lug *g* projecting forwardly of the spring clip *f* has its lateral 45 edges *g'* doubled over to form opposed channel guides in which the lug *e* upon the case *a* is arranged to slide, to an extent limited by the upturned end *e'* of the lug *e* which constitutes a stop. In this way it is possible to 50 push back the case *a* when it is found to be in the way of the user of the telephone.

A still further modified form of construc-

tion illustrated in Figs. 7 and 8 has the case *a* rigidly mounted upon the spring clip *f* by means of a forwardly projecting lug *j*. 55 This construction is intended for use in cases where movement of the disinfecting device with relation to the telephone mouth-piece is not required.

I claim:—

1. Apparatus for disinfecting telephone mouth-pieces comprising a cylindrical container and a spring clip adapted to embrace the neck portion of a telephone mouth-piece and to support the container in a horizontal 65 position above the front edge thereof.

2. Apparatus for disinfecting telephone mouth-pieces comprising an open ended cylindrical container, a removable closure for the end of said container and a spring clip 70 adapted to embrace the neck portion of a telephone mouth-piece and to support the container in a horizontal position above the front edge thereof.

3. Apparatus for disinfecting telephone 75 mouth-pieces comprising a cylindrical container, a spring clip adapted to embrace the neck portion of a telephone mouth-piece and to support the container in a horizontal position above the front edge thereof and 80 means connecting the container and clip, said means permitting movement of the container in relation to the clip.

4. Apparatus for disinfecting telephone 85 mouth-pieces comprising a cylindrical metal container, having openings, a removable end closure for said container, a spring clip arranged to engage a telephone mouth-piece, a lug attached to the container, a lug attached to the spring clip and means movably connecting the two lugs. 90

5. Apparatus for disinfecting telephone 95 mouth-pieces comprising a cylindrical metal container, a removable end closure for said container, said container having openings to permit the escape of disinfecting gases therefrom, a spring clip engaging the telephone mouth-piece, a lug attached to the container, a lug attached to the spring clip and means 100 pivotally connecting the two lugs.

In testimony whereof he has affixed his signature.

PATRICK SHAUGHNESSEY O'DONNELL.
